Patented Oct. 11, 1921.

UNITED STATES PATENT OFFICE.

IRVING J. FOLTZ, OF SEATTLE, WASHINGTON.

REGULATOR.

1,393,615.

Specification of Letters Patent.

Patented Oct. 11, 1921.

Application filed May 1, 1920. Serial No. 378,207.

To all whom it may concern:

Be it known that I, IRVING J. FOLTZ, a citizen of the United States, and a resident of Seattle, in the county of King, State of Washington, have invented a new and Improved Regulator, of which the following is a full, clear, and exact description.

This invention relates to a regulator, and more particularly that class of regulator intended for use in connection with a gas burner.

An object of my invention is the construction of a regulator of the type specified by means of which the burner may be caused to produce a "pilot" size flame or one in which the entire battery of burners may exert their maximum output together with all intervening amounts of flow between these two extremes.

A further object of my invention is the provision of a regulator including a valve, and seat therefor which valve will be self centering when in said seat.

A still further object of my invention is the construction of a regulator from which the gas will be thrown straight into the mixing tube of the burner to produce an ideal mixture, and consequently a good flame.

Another object of my invention is the provision of a regulator in which the parts are so constructed and coöperate in such a manner that a minimum wear is produced so that the regulator will always remain in perfect condition.

Further objects of my invention will appear in the annexed specification and drawings, which latter illustrates one practical embodiment of my invention and in which—

Figure 1 is a sectional side view of a gas burner having applied thereto my improved type of regulator.

Fig. 2 is a sectional end view of the same taken along lines 2—2 of Fig. 1.

In all of these views like reference numerals designate similar parts, and the reference numeral 5 indicates the mixing chamber of a burner, and 6 the tube leading from the generator, connection between these two being provided by means of a further tube 7 interposed between and connected to the first named elements.

The regulator is positioned within the tube 7 and conveniently includes a cap 8 formed with a tapered opening, the cap being held in applied position by means of

screw threads such as 10 coöperating with the screw threads formed in the inner face of the tube 7 and adjacent the forward end thereof.

The regulator also comprises a spindle 11 provided adjacent its rear end with any suitable rotating means such as a handle 12 which spindle is formed adjacent its forward end with a reduced portion 13 to the rear of which screw threads 14 are provided which screw threads coöperate with screw threads in the bore face of the tube 7, any suitable packing means such as 15 inclosing the spindle 11 and rear end of the tube to prevent a leakage of gas at this point.

The reduced portion 13 of the spindle 11 terminates in a portion 16 triangular in cross section, as has been clearly shown in Fig. 2, the corners of said triangular portion bearing against the inner face of the cap 8. Associated with the forward end of the portion 16 of the spindle 11 is a tapered shank 17, the inclined face of which extends through the tapered opening 9 so that an orifice of proper diameter is provided around the tapered point in the right proportion to the gas it can pass.

A yoke 18 conveniently has one of its ends encircling the tube 7, its opposite end extending beyond the packing means 15, as has been clearly shown in Fig. 1 and encircling the spindle at this point. A suitable stop is secured to the spindle 11 adjacent this point, which stop conveniently includes a collar 19 and set screw 20 for holding the said collar in position.

It will now be appreciated that in operation the triangular portion 16 of the spindle 11 will bear against the inner face of the cap 8, and by virtue of the small amount of wear, that the shank 17 will always be retained in central position with respect to the tapered opening 9.

Upon a rotation of the spindle, it will be understood that the same will be projected or retracted by means of the screw threads 14 or other expedient used to move the spindle longitudinally of the tube 7. This movement will result in a more restricted or enlarged space existing between the outer face of the shank 17 and the face of the opening 9 of the cap 8, and by means of this construction the amount of gas passing between these members may be varied at will, at the same time forming a proper sized orifice. It will

further be understood that no seating of the shank 17 within the opening 9 of the cap 8 will occur by virtue of the fact that the stop associated with the spindle 11 will prevent an inward motion on the part of the spindle beyond the pre-determined point.

By means of this construction, the tapered shank is prevented from seating as aforesaid in the orifice. The stop is so set that the 10 pilot or generator heater will only burn when the regulator is in as nearly closed position as possible. The stop may be set at a point at which a constricted opening exists between the orifice opening 9 and the 15 shank 17 so that the first gas generated may not escape too easily, thus preventing an easy starting. Further if the stop were 20 eliminated the shank would seat within the opening which would quickly become too large because of wear for practical purposes, and would result in the shank and cap both having to be renewed.

This would practically be the case if the shank were left in seated position within the 25 opening while the parts were hot.

Obviously upon the metal cooling the contraction would cause a great mutilation of the bore of the opening, and in some instances would cause a sticking of these parts.

30 The burner is shut off by means of a valve (not shown) in the supply line, and it will further be appreciated, as an advantage derived from the stop that if these parts co-act to close the opening that the generator 35 would fill with kerosene making it extremely difficult to generate the gas the next time the burner was set in operation.

The shank further acts as a cleaner for the 40 opening, and the regulator may be cleared of small particles of various material by re-tracting the spindle 11 to its extreme position while the burner is in operation so that the particles will be blown out through the 45 larger orifice thus formed, as the pressure in the regulator is about the same as in the supply tank, from 20-35 pounds.

Also the cap 8 may be tightened by retracting the spindle and the stop may subsequently be re-set to conform to the new setting of the parts.

Finally by means of the triangular portion 16 of the spindle a positive centering of

the shank within the opening or orifice 9 is provided and no adjustment of these parts will be necessary during the subsequent operation of the burner.

Obviously numerous modifications of structure might be resorted to without in the least departing from the scope of my claims,

What I claim as new and desire to secure by Letters Patent is as follows:—

1. A regulator, including a tube, a constricted opening at the rear end of said tube, a spindle projecting within said tube, the inner end of said spindle being adapted to 65 co-act with said opening, a stop including a collar, a set screw associated with said collar, said collar being adapted to encircle said spindle and being secured thereto by means of said set screw, and a yoke having 70 one of its ends encircling said tubing and its opposite end encircling said spindle whereby to co-operate with said stop to limit the inward motion of said spindle.

2. A regulator, including a piece of tubing, a cap secured to one end of said tubing, said cap being formed with an opening, a spindle projecting through said tubing and cap the outer end of said spindle extending through said opening, and means forming 80 part of said spindle for holding the same centrally with respect to said tubing and cap.

3. A regulator, including a piece of tubing, a cap secured to one end of said tubing, said cap being formed with an opening, a 85 spindle projecting through said tubing and cap, the outer end of said spindle extending through said opening, and means forming a part of said spindle and co-operating with the inner face of said cap for holding said spindle centrally with respect to said tubing.

4. A regulator, including a piece of tubing, a cap secured to one end of said tubing, said cap being formed with an opening, a spindle projecting through said tubing and 95 cap, the outer end of said spindle extending through said opening, said spindle being triangular in cross section adjacent its inner end portion, such triangular portion contacting with the inner face of said cap 100 whereby to hold the said spindle centrally with respect to the cap opening and tube.

IRVING J. FOLTZ.
